UNITED STATES PATENT OFFICE.

WILLIAM L. SAUNDERS, OF JERSEY CITY, NEW JERSEY.

QUARRY-DRILL FRAME.

SPECIFICATION forming part of Letters Patent No. 340,251, dated April 20, 1886.

Application filed December 31, 1885. Serial No. 187,238. (No model.)

To all whom it may concern:

Be it known that I, WILLIAM L. SAUNDERS, a citizen of the United States, residing at Jersey City, in the county of Hudson, State of New Jersey, have invented certain new and useful Improvements in Quarry-Drill Frames, of which the following is a description.

The present invention relates to improvements in quarry-drill frames; and it consists in so arranging the rack-bar upon which the drill is mounted that it is separable from and adjustable within the cross-heads to which the supporting-legs are secured, and also in so supporting the rack-bar within the cross-heads that it may be partially rotated therein, so as to bring the drill in any desired position from vertical to horizontal. The details of construction will be hereinafter set forth.

In the accompanying drawings, Figure 1 is a perspective view of my improved quarry-drill frame with the drill in a vertical position. Fig. 2 is an elevation of one of the cross-heads. Figs. 3 and 4 are details of one of the leg-clamps.

Similar letters denote like parts.

A is a bar of angle-iron, and B is a rack permanently secured against one flange thereof. C are sectional circular bearings, through which pass the angle-bar A, which, as indicated, has a firm bearing therein, and is also suitably apertured to permit the passage of the rack. The bearings C are mounted in cross-heads D, being secured in position by the removable upper portion, d, thereof, which, by means of suitable set-screws, E, can be loosened to permit the rotation of the circular bearing C and the axial adjustment of the bar within the cross-head, or readily displaced to allow the removal of the bearing C, in whole or in part, and also the bar A, whenever desired. The cross-head is suitably apertured at its extremities to receive the leg-clamps F, which are short round-headed bolts formed with elongated apertures f, through which pass the legs G, which are then secured in position by means of set-screws g. The clamps F pass obliquely through the ends of the cross-heads, where they may then be secured by means of set-screws H. The legs are passed through their clamps and set outward and away from each other to give the desired stability to the frame, and then secured in

position by means of their set-screws, which secure the legs in position, and at the same time draw the heads of the clamps tightly 55 against the ends of the cross-heads. The set-screws H may then set against the leg-clamps as an extra precaution, although in many instances they may be dispensed with altogether.

Upon the frame thus formed is mounted any 60 suitable form of drill, I, which is provided with suitable pinion, i, mounted upon its saddle and meshing with the rack B, and a crank, J, connected therewith, by means whereof the drill is moved by hand into the desired position 65 along its supporting-bar.

A gib, K, and suitable set-screws, L, are attached to the saddle of the drill, so that it may be fixed upon the bar at any desired point, and the cross heads, together with the legs, 70 may be placed in any position upon the bar, and the drill may be operated either between the two sets of legs, as here shown, or to the right or left of the legs, as desired. The purpose of this is to enable the drill to operate 75 close to the corner and at the end of the bench.

Where it is desired to put in holes with the drill in a horizontal position on a line with the floor, the drill and bar are together swung on the two cross-pieces as axis, and lowered on 80 the legs until the drill-cylinder nearly meets the floor. This is done by loosening the bolts on the top of the cross-pieces and leg-clamps, and pulling the drill over to any desired position.

In using the machine for broach-channeling, a line of holes is driven, leaving a dividing-wall of about three-quarters inch between the holes. When these holes are completed to the depth and extent required, the rotation 90 of pawls are taken out from the back head of the cylinder, and the drill is made to break down the dividing-walls by means of a broach and without rotating the piston.

Having described my invention, what I claim 95 is—

1. In a quarry-drill frame, the combination of a bar, a drill mounted thereon, removable supports for the bar, and means for adjusting the bar both longitudinally and axially within its supports, substantially as described.
2. In a quarry-drill frame, the combination of a horizontal rack-bar, a drill mounted and moving thereon, removable end supports for

the bar, and means, as described, for adjusting the bar both longitudinally and axially within its supports, as set forth.

3. In a quarry-drill frame, the combination of a horizontal rack-bar, vertically and longitudinally adjustable end supports therefor, divisible circular bearings for said bar mounted within the end supports and capable of rotation therein, and a drill mounted and

adapted to be moved laterally upon the bar, to substantially as shown and described.

In testimony whereof I hereto affix my signature in presence of two witnesses.

WILLIAM L. SAUNDERS.
